ATTORNEY

UNITED STATES PATENT OFFICE.

JOHN FITZGERALD, OF NEWARK, NEW JERSEY.

SCISSORS-SHARPENER.

No. 899,213.

Specification of Letters Patent. Patented Sept. 22, 1908.

Application filed October 24, 1907. Serial No. 398,859.

To all whom it may concern:

Be it known that I, JOHN FITZGERALD, a citizen of the United States, residing at Newark, in the county of Essex and State of New Jersey, have invented certain new and useful improvements in Scissors-Sharpeners; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

15 This invention relates to a device for sharpening shears and similar articles, and consists of a block to be grasped by the hand and to be slid back and forth along the cutting edge of a blade, and is designed, particularly, for such blades as shear blades, where one of the cutting edges is perpendicular and the other chamfered or beveled.

20 The invention consists more particularly in supplying a sharpener that has a guiding means for holding the blade at the proper angle to the grinding surface to cause a proper preparation of the cutting edge.

The invention is illustrated in the accompanying drawing, in which

30 Figure 1 is a perspective view showing the sharpener as it is applied to a blade of a pair of shears, and Fig. 2 is an end view of the sharpener with the blade in section.

The sharpener consists of a suitable block 35 10 which may be made of any suitable material, but is preferably made of wood, and it has inserted therein a grinding bar 11 which is provided, on its top surface, with an abrasive conformation being preferably cut with 40 file teeth, although any substitute such as emery may be installed. The block 10 is

recessed, longitudinally, above the grinding bar 11, one side of the recess having a perpendicular wall 12, the other wall of the recess being inclined as at 13, at an angle, to bring the blade 15 properly onto the grinding surface so that when it is slid back and forth along the grinding bar, the blade will be maintained at the same angle to the grinding surface, and the blade is sharpened the same from one end to the other.

To prevent the accidental displacement of the blade from its position, I may undercut, as at 14, the lower part of the perpendicular wall 12 of the recess of the block.

55 This sharpener is simple to make, and can be operated by anybody, since the angular sharpening necessary on the scissors or shears is insured.

Having thus described my invention, what I claim is:

A sharpener for shears comprising a block having a grinding bar longitudinally arranged therein, the block being recessed above the grinding bar, one wall of the recess being perpendicular and having a slightly undercut portion adjacent to the grinding bar, the other wall of the recess being inclined at an angle to the grinding bar and being approximately parallel with the undercut portion of the perpendicular wall, whereby a blade inserted in the sharpener is maintained at a proper angle to the grinding bar, and can only be withdrawn in a direction substantially parallel to the inclined wall.

75 In testimony, that I claim the foregoing, I have hereunto set my hand this 21st day of October 1907.

JOHN FITZGERALD.
